Primary Examiner — T Chase Nelson*Assistant Examiner* — Kelly L Gross(74) *Attorney, Agent, or Firm* — MEDLER FERRO
WOODHOUSE & MILLS PLLC(57) **CLAIM**

The ornamental design for laboratory instrument, as shown and described.

DESCRIPTION

FIG. 1 is a top, front, right side perspective view of a laboratory instrument showing an embodiment of our new design;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a top plan view thereof; and,

FIG. 7 is a bottom plan view thereof.

The equal length broken lines illustrate portions of the laboratory instrument that form no part of the claimed invention. The solid horizontal line shading illustrates portions of the laboratory instrument that are blue; the broken horizontal line shading illustrates portions of the laboratory instrument that are grey; and the solid black shading illustrates portion of the laboratory instrument that are black.

1 Claim, 4 Drawing Sheets(56)
